UNITED STATES PATENT OFFICE

ALBERT L. HOWARD, OF BROCKTON, MASSACHUSETTS, ASSIGNOR TO HAMILTON-WADE COMPANY, OF BROCKTON, MASSACHUSETTS, A CORPORATION OF MASSACHUSETTS.

FINISHING WELT AND METHOD OF MAKING THE SAME

Application filed December 31, 1929. Serial No. 417,807.

This invention relates to finishing welt or binding for use in connection with upholstery or for other decorative finish. A finishing welt constructed according to this invention is particularly useful in the interior finish of 5 automobiles and other places where materials used are subject to considerable wear or exposure to weather conditions, although the invention is of more general application.

10 The purpose of my invention is to provide a finishing welt presenting a particularly attractive and symmetrical appearance and which may be attached readily and securely by headed fasteners which are concealed and 15 protected by the welt.

In one aspect my invention consists in improvements in finishing welt of the type disclosed in application for patent of Albert L. Howard, Serial No. 413,771, filed December 20 13, 1929. The particular advantage of the present invention over that disclosed in above-identified application is that in the present construction the parts are connected by means of concealed stitching and the stitched edges 25 also are concealed and protected thereby. The present arrangement differs from the construction shown in the application also in that no upstanding marginal beads are employed but a simple flat base effect is produced to give a smooth appearance to the binding, and is more particularly adapted for use where a more nearly unbroken surface is desired. This is accomplished by producing a bead in which there is positioned a 30 35 filler about which is wrapped a body strip, one edge being sewed to one edge of a base strip and the other edge of the body strip passing over and cemented around the sewed edges. However, one or more beads might 40 be used by slight modification.

In another aspect my invention consists in a welt of the character under discussion, in which a bead is secured to a base portion by 45 means of stitching concealed by other connecting means passing around it, the stitching being so located as to prevent separation of the parts and reinforcing the connection, which may be otherwise cemented, thereby 50 giving the effect of a separately stitched hinge

portion which is cemented into a covering therefor holding the parts in place.

The invention includes also within its scope a novel method of preparing and manufacturing the improved form of welt herein disclosed, said method being characterized by the steps of stitching the superposed edges of the two strips to one edge of a filler and then wrapping the material of one strip about the filler and bringing into contact with the folded edge of the other strip.

These and other features of the invention will be best understood and appreciated from the following description of a preferred embodiment thereof, selected for purposes of illustration and shown in the accompanying drawing, in which

Fig. 1 is a view in perspective of the main body strip attached to the base strip;

Fig. 2 is a similar view showing the filler strip in position on the main body strip;

Fig. 3 is a similar view showing the main body strip partially turned around the filler strip;

Fig. 4 is a view of a completed form of the 75 welt; and

Fig. 5 is a view in perspective of the completed welt with bead portion turned up as is necessary in attaching the welt in position.

A main body strip 10, as shown in Fig. 1, 80 may be composed of a continuous strip of leather, fiber or other equivalent material having finished or decorative surface, and is attached to a base strip 12 by means of stitching 13 adjacent the registering edges 15 and 16 of the respective strips. The edge 17 opposite to the registering edge 16 of the base strip 12 is turned or folded under and cemented in place to provide a finished edge. 85 These two strips may be of the same material or different materials, or may be of different colors, depending upon the effect desired and the type of work to be done.

In the next step, a half-round filler 19 may 90 be positioned with the edge of its flat or other shaped base along the line of stitching 13 adjacent the edge 15 of the body strip 10 after having covered adjacent surfaces with cement or other similar compound. The free edge 22 of the body strip 10 is then wrapped around 95 100

the filler strip 19, and the surfaces pressed into contact to insure complete union of the cemented areas. The position of the parts during this operation is more clearly shown in Fig. 3, wherein contact has been made by the strip 10 with substantially one-half the upper convex surface of the filler strip. The free edge 22 of the strip is then wrapped around the sewed edges 15 and 16 of the body and base strips respectively, with the edge 22 terminating adjacent to or contacting with the turned under edge 17 of the base strip, as shown in Fig. 4. A bead 23 is thus formed by the filler 19 and surrounding portion of the body strip 10, hinged to the base at or adjacent to one edge of the welt.

After completion of the welt, fastening nails or brads 25 may be applied through the base strip and the end of the main body strip by raising the bead 23. The position of the filler for inserting nails for securing the welt in position is shown in Fig. 5. When released, the bead will again assume its normal position, as shown in Fig. 4. The nail passes through both the base strip and the main body strip, thus holding the parts in still more firm position after the welt has been attached. The width of each strip is properly proportioned so as to cause the edge 17 of the base strip to lie in contact with or adjacent to the folded under edge 22 of the body strip 10.

It will be noted that by arranging the parts as described both the stitching and registering edges of the two strips will be protected from undue wear and weather conditions which might be likely to affect durability. The only opening through which entrance may be obtained to the stitching is through the opening between the bead and the base strip, but this opening is normally substantially closed after the strip has been applied in position. Only a single line of stitching is required to fasten the parts. The filler may be composed of any suitable material, such as rubber or other composition, and a clearance groove may be formed in the flat side of the filler to permit the bead to lie flat upon the base strip, thus adding further protection to the welt. A filler having a cross-sectional different from that described could be substituted to suit the particular use or effect intended.

The construction is such as to lend itself to easy manufacturing operations and permits the parts to be assembled in orderly steps. The filler strips may be separately carried in stock and the attached body and base strips applied when desired in colors or materials best suited for the requirements of the case. The effect of the attached bead is also symmetrical and pleasing to the eye, and from a mechanical standpoint presents every advantage of convenience in attachment and durability in wear. It is also possible to accomplish substantially the same result without

using a separate base strip by forming a tubular element of covering material, inserting a filler in one portion and cementing the filler and base portions in place in the same form as that which results in the use of a separate base strip.

Having thus described my invention, what I claim as new and desire to secure by Letters Patent of the United States is:

1. A finishing welt having a bead including a filler core surrounded by a body strip, a base strip having one of its edges stitched to an edge of said body strip adjacent to and laterally of said bead, an unstitched portion of said body strip being secured to and covering the said stitched edges.

2. A finishing welt having a filler core, a body strip wrapped around said filler core with one edge of the strip adjacent to an edge of the filler core, a base strip having an edge registering with an edge of the body strip, stitching laterally outside of the filler core and adjacent to an edge thereof passing through portions of said strips adjacent to said registering edges, said body strip being folded over and covering said edges and stitching.

3. A finishing welt having a base strip and a body strip including a bead, said bead comprising a filler core wrapped within an intermediate portion of the body strip and one edge portion of the body strip being sewed to said base strip outside and laterally of the filler core and the other edge portion thereof being disposed laterally of the bead and cemented about said sewed edge.

4. A finishing welt comprising a filler extending longitudinally thereof and wrapped within a strip element of the welt, one edge portion of the element being stitched to an edge portion of a second strip element along a line outside of but adjacent to one edge of the filler and the loose end of the first element being wrapped about the filler and about the stitched edge portions of the elements, the stitches normally holding the wrapped filler in contact with the second strip element but permitting the filler to be pivoted upwardly about the stitches.

5. A finishing welt comprising a filler extending longitudinally thereof and wrapped within a strip element of the welt, a second strip element having one edge portion folded onto itself from beneath and forming a fold vertex at an edge of the welt, one edge portion of the first element being stitched to the unfolded edge portion of the second element to one side of the filler and the loose end of the first element being wrapped about the filler, about the stitched edge portions of the elements, and against the bottom of the second element in the plane of the folded edge portion thereof.

ALBERT L. HOWARD.
